UNITED STATES PATENT OFFICE.

GRANT CAMPION AND MOTT WYANT, OF ANDERSON, INDIANA.

GAS-PRODUCER.

No. 830,968.

Specification of Letters Patent.

Patented Sept. 11, 1906.

Application filed June 22, 1905. Serial No. 266,404.

To all whom it may concern.

Be it known that we, GRANT CAMPION and MOTT WYANT, citizens of the United States, and residents of Anderson, in the county of

5 Madison and State of Indiana, have made a certain new and useful Invention in Gas-Producers; and we declare the following to be a full, clear, and exact description of the same, such as will enable others skilled in the art to 10 which it appertains to make and use the invention, reference being had to the accompanying drawings, and to letters and figures of reference marked thereon, which form a part of this specification.

15 Figure 1 is a central vertical section on the line 1 1, Fig. 3. Fig. 2 is a central vertical section on the line 2 2, Fig. 3. Fig. 3 is a transverse section on the line 3 3, Fig. 2. Fig. 4 is a plan view of our gas-producer.

20 The invention relates to apparatus for the manufacture of gas; and it consists mainly in the improvements upon a gas-producing apparatus or plant shown and described in Letters Patent No. 745,781, dated December

25 1, 1903.

In the accompanying drawings, illustrating the invention, the letter *a* designates the circular wall of the gas-producer, which consists of brickwork having proper jacketing of

30 sheet-iron or steel. This wall or body portion is supported upon four arcuate foundation-piers *b*, which bound the branches *f* of the cruciform water-bosh *w*, which extends outward from the circular central basin *v* under the circular wall *a* to the shelving-walls *c* of the exterior or open end portions of said

35 branches.

In the construction shown the body-wall *a* is externally cylindrical, and the interior surfaces of the upper and lower sections or portions (indicated at 2 and 4) are also cylindrical, the diameter of the latter portion being less than that of the upper portion. The thickness of the lower portion of the wall is, 40 however, greater than that of the upper portion, and such thickness is uniform around the section. The upper section is connected to the lower section by a portion of the wall, the inner surface 3 of which is of conical 45 form, shelving downward and inward from the upper surface 2 to the lower surface 4. Below this shelving-wall surface the inner surface 4 of the lower section extends downward vertically to the arc-form ledges *d* of

the foundation-piers *b*, which project inward 55 a short distance beyond the line of said surface 4 and provide arc-form wall-faces 5 of the middle basin *v* of the water-bosh.

In the basin are secured to its bottom four 60 columns 6, which are preferably of iron and are located at the corners of a square, each column or post 6 being separate from, but opposite to, one of the arc-form walls of the central basin of the water-bosh. Each column or post is usually made with a horizontal bottom flange or foot 7, which is secured in the cement of the floor of the basin, and its upper end is provided with an angular bearing-plate 8 to receive and support the angular inner corner of a bearing-shoe *e*, which rests on 65 the foundation-ledged. This shoe *e* is provided with a downward-extending flange *m*, which is deep enough to have its lower edge immersed in the water of the water-bosh, so as to form, in connection with the platings of the 70 angular bearing 8 and the bridge-plates 9, over the inner openings of the branches of the water-bosh, a gas-tight joint.

On the shoes *e* are supported four angular shelving-grates *g*, which extend downward 80 and inward from the upper portion of the lower cylindrical surface a short distance below the shelving-surface of the body-wall. The ridge-line of the angular grate is inclined downward and inward, and from the ridge- 85 line the wings of the grate shelf laterally downward. The rear margins of the wings, which fit against the cylindrical wall-surface are elliptically curved. Brace-bars *u* are seated in bearings *j* of the shoes *e* and serve to 90 hold them in relative position, thereby also strengthening the columns 6. Between the four grates is a cruciform opening to the central basin, the four branches of which correspond to the four branches of the water-bosh. The 95 angular interspace behind each grate forms an air-chamber, which communicates with a radial passage *h* through the body-wall, said passage being provided at its outer end with a gate *k*, in connection with which is a pipe 100 *p* for supplying steam and air, or either, according to requirement. The bottom of this passage *h* is about level with the horizontal plane of the shoe *e*.

Between the passages *h* are provided, 105 through the body-wall, the radial passages *p'*, the bottoms of which are at a somewhat higher level than those of the passages *h*.

These passages p' are also provided with gates and are designed to serve for inspection of the fuel-bed at the location of the grates and for such operations in connection with 5 such bed as may be necessary from time to time. These passages p' are immediately over the branches of the water-bosh.

The top t of the chamber within the body-wall is spherically arched and is provided 10 with poke-holes s between the hoppers r . Each poke-hole is provided with an arming-plate 10 and a lid 11, which is hinged to said plate. The arming or seat plate is provided with a threaded seat 2' to receive a valved 15 union-joint 16, designed to connect with a steam-supply pipe. When the poke-hole is opened for inspection or working of the fuel-bed, steam is turned on to check the escape of gas through said hole, thereby enabling the 20 work to be attended to without this very serious obstruction and saving the gas which would be otherwise wasted.

There are designed to be four hoppers r , which are located, respectively, over the 25 grates g . Each hopper is provided with a cover having an inclined marginal flange, which is designed to fit an inclined flange-seat at the upper end of the hopper-passage. At its lower portion the wall of the hopper-passage, which is rectangular, is slotted 30 through one side for the passage of the slide gate or valve g' , which is operated by means of a lever 12, having a cross-head 13, which is connected to lugs of the slide-gate by parallel 35 rods 14. The gate moves on lateral ways of a bearing-plate 15, to which the hopper is bolted.

The exit-opening, through which the gas is carried to the lines of distribution, is indicated 40 at 17.

In this apparatus angular corners and recesses in the fuel-chamber are avoided above the gratings, and these gratings are designed to spread laterally and toward the center of 45 the fire-bed to a greater extent than when located in rectangular corners. The hoppers being respectively arranged vertically over the grates facilitates the feed thereto in accordance with their action on the fuel-bed. 50 The wall being circular at all heights is designed to obviate choking, especially over the grates, and the wide circular middle basin of the water-bosh being nearly of as great diameter between the foundation-piers as the 55 lower portion of the fuel-chamber affords great facility to the operator in working and removing the pile of ash and cinder under the fuel-bed.

Having described the invention, what we claim, and desire to secure by Letters Pat- 6c ent, is—

1. In a gas-producer, the body-wall, having an interior conical shelving-surface between an upper cylindrical surface and a lower cylindrical surface, and arc-form foundation-piers supporting said body-wall and projecting inward to provide bearing-ledges, substantially as specified. 65

2. In a gas-producer, a body-wall having an interior cylindrical surface below a conical shelving-surface, and four ridged angular grates having elliptical rear edges fitting said cylindrical surface, substantially as specified. 70

3. In a gas-producer, the combination with a body-wall and arc-form ledged foundation-piers, of a water-basin having four columns, rectangularly placed opposite to and separate from said piers, and grate-shoes supported by said piers and columns, substantially as specified. 75

4. A gas-producer, having four shelving angular gates in its lower portion, and vertically over each grate, a hopper, substantially as specified. 80

5. In a gas-producer, the combination 85 with a cylindrical body-wall and a cruciform water-bosh of four arc-form foundation-piers bounding a circular central basin of said water-bosh, and four columns in said central basin opposite said piers, substantially as specified. 90

6. A gas-producer, consisting of a cylinder-form body-wall, arc-form piers supporting the same, a cruciform water-bosh having a circular central basin bounded by said piers, 95 supporting-columns in said basin opposite said piers, grate-shoes bearing on said piers and columns, shelving-grates on said shoes and hoppers over said grates, substantially as specified. 100

7. A gas-producer body having a circular interior wall-surface consisting of a conical shelving intermediate portion between its upper and lower cylinder-form portions, in combination with a cruciform water-bosh, 105 arc-form foundation-piers, and columns in said water-bosh, four angular shelving-grates, and four hoppers respectively above said grates, substantially as specified.

In testimony whereof we affix our signatures in presence of two witnesses.

GRANT CAMPION.
MOTT WYANT.
